UNITED STATES PATENT OFFICE.

LUDWIG GLANZER, OF WINKLER, KANSAS.

RAIL JOINT.

Application filed December 9, 1922. Serial No. 605,767.

To all whom it may concern:

Be it known that I, LUDWIG GLANZER, a citizen of the United States, residing at Winkler, in the county of Riley and State of

5 Kansas, have invented certain new and useful Improvements in Rail Joints, of which the following is a specification.

This invention relates to improvements in rail joints, with special reference to connecting the abutting ends of rails as used in track-way construction.

10 The principal object of the invention is to provide means for preventing the relative vertical movement of adjacent abutting rails.

Another purpose is to provide means combined with the fish plates adapted to prevent separation of the rails longitudinally.

15 A further aim is in the provision of connecting and securing means that can be readily applied at a moderate expense and which are of simple construction.

These and like objects are attained by the novel construction and combination of parts 20 hereinafter described and shown in the accompanying drawing, in which:—

Figure 1 is a side elevational view of a pair of a conventional type of rails showing the application of the invention.

25 Figure 2 is a similar view of the same, the fish plates being removed.

Figure 3 is a transverse sectional view taken on line 3—3 of Figure 1.

Figure 4 is another like view taken on line 4—4 of Figure 1.

In the drawing, the numerals 10 and 10' 30 designate a pair of ordinary track rails shaped as usual with head, web and base flange.

Formed in the webs 11 and 11' are semi-circular recesses 12 and 12', and drilled in the base flanges 13 and 13', in each side of the webs, are paired openings 14 and 14', these recesses and drilled openings being the 35 only operations performed on the rails.

A disc 15, slightly less in thickness than

the rail web, is fitted to be received in the opposed recesses 12 and 12', acting in the manner of a key to prevent relative vertical movement in an obvious manner.

50

Said disc contains an axial opening 16 through which passes a bolt 17, extending through the clamps or fish plates 18, applied to the sides of the webs as shown, the bolt being disposed at the center of the length 55 of plates, its head 19 being drawn against one of the plates by a nut 20 on the bolt impinging against the opposed plate.

These fish plates are suited to be received between the heads 10 and 10' and base 60 flanges 13 and 13' of the rails, and have rigidly fixed in their lower edge, pairs of pins 21 spaced and suited to freely engage in the holes 14 and 14', being bevelled at their lower ends to readily enter.

65

In applying the fastenings, the rails having been previously recessed at their ends and drilled through their flanges, the disc 15 is inserted, the pins 21 entered into the holes and the fish plates secured by the bolts, 70 thus holding the rails in register and preventing relative movement of the same in any direction.

Having thus described my invention, what I claim as new and desire to secure by Letters Patent, is:—

75

A track rail joint fastening comprising in combination with a pair of rails having paired circular openings in their flanges on each side of and adjacent the webs thereof, 80 of a pair of fish plates suited to the rails, said rails having registering semi-circular recesses in their abutting ends, of a circular disc filling the mentioned recesses, round pins extending rigidly from the lower edges 85 of said fish plates engaging in the flange openings, and a bolt passing through said fish plates and an opening in said disc.

In witness whereof I have affixed my signature.

LUDWIG GLANZER.
